EX

DESIGN.

—o—

LE ROY W. FAIRCHILD.

MATCH BOX.

No. 18,794.

Patented Dec. 11, 1888.

UNITED STATES PATENT OFFICE.

LE ROY W. FAIRCHILD, OF NEW YORK, N. Y.

DESIGN FOR A MATCH-BOX.

SPECIFICATION forming part of Design No. 18,794, dated December 11, 1888.

Application filed November 13, 1888. Serial No. 290,712. Term of patent 3½ years.

To all whom it may concern:

Be it known that I, LE ROY W. FAIRCHILD, of New York, in the county of New York and State of New York, have invented a certain 5 new Design for a Match-Box, of which the following is a specification.

This invention consists of a design for match-boxes.

The accompanying photograph is a face 10 view of a box having my design thereon.

The design in this case consists of a human face having a mustache and heavy eyebrows, the face being shown as in a front or face view. The face is surrounded by a border 15 made to represent a hood made of the skin of a bear or some similar animal, it being drawn close around the face and so fashioned as to show the representation of the end of a paw projecting from within the hood and hanging

over the edge at one side near the bottom, 20 and with two projections at the top, one at each side, representing the ears of the animal.

The outline of the box is made slightly oval at the sides, being widest across the center, with a slight indentation on each side a short 25 distance from the bottom and also at the center of the bottom, so that when held up before the face it will represent a bear in a sitting posture.

I claim—

The design herein described and shown for 30 a match-box.

In witness whereof I hereunto set my hand in the presence of two witnesses.

LE ROY W. FAIRCHILD.

Witnesses:

J. R. CAMPBELL,
VICTOR W. BRUNDAGE.
